UNITED STATES PATENT OFFICE.

HENRY L. PLUMMER, OF PETERSBURG, VIRGINIA.

APPARATUS FOR MANUFACTURING DRESS-SUITCASES.

1,359,427.

Specification of Letters Patent. Patented Nov. 16, 1920.

Application filed October 13, 1917. Serial No. 197,478.

To all whom it may concern:

Be it known that I, HENRY L. PLUMMER, a citizen of the United States, residing at Petersburg, in the county of Dinwiddie and State of Virginia, have invented certain new and useful Improvements in Apparatus for Manufacturing Dress-Suitcases; and I do hereby declare the following to be a full, clear, and exact description of the invention, such as will enable others skilled in the art to which it appertains to make and use the same.

This invention relates to paper box and like constructions and more particularly to the construction of elements in the erection of suit cases.

It is one of the objects of the present invention to provide a process for the manufacture and also to provide an apparatus for the practice of the process whereby the principal bottom or body member of dress suit cases, for instance, can be made economically, rapidly and accurately, and particularly to provide for the production of dress suit case bottoms of various sizes. It is another object of the present invention to provide an apparatus, capable of ready adjustment to facilitate the manufacture of dress suit case bottoms or the like, and especially to provide an apparatus having relatively adjustable male and female cutting members to facilitate the cutting of the blanks to the desired and requisite outline.

With these and other objects in view, the present invention consists in the method of and apparatus for manufacturing blanks for box constructions and especially for the manufacture of dress suit case elements, one form of apparatus for practising the method being illustrated in the accompanying drawing, in which,

Figure 1 is a plan view of one form of blank,

Fig. 2 is a perspective view of the folded blank,

Fig. 3 is a plan view partly in section showing one part of a machine or apparatus for cutting the stock, and,

Fig. 4 is a vertical section partly in elevation of the apparatus.

The present invention contemplates particularly the production of the bottom or body element of a dress suit case, a form of which is illustrated in plan view in Fig. 1 and which is shown in folded position in Fig. 2. The blank comprises a substantially

oblong central panel 2 which may be of suitable proportions and is foldable along lines A and B, the outer portions 3 and 4 forming the sides of the box element, these latter sides being foldable on lines c and d to form flange e and are similarly foldable at their ends to form flanges f-f, the bottom 2 having also end flanges g. The common practice in the manufacture of boxes of this type in order to facilitate the proper folding of the bottom member has been to nick from corners h-h of one side of a previously cut blank chips forming notches of suitable outline and then to transfer the blank from which the corner notches have been chipped or cut to another machine and then to cut out the intermediate angular chips forming notches i-i. In this practice, the corner notches h-h at one side of the bottom, have been cut out and the blank turned side for side and the other corners chipped out. One of the particular objects of my present invention is to provide a process for manufacturing these blanks which contemplates simultaneously cutting the required notches throughout the entire blank at one single step or if preferred, may be practised by the cutting of all of the notches h-h and i-i at one side only of the blank which then may be reversed side for side and all of the notches at the other side cut.

To secure this step in the manufacture of the box bottom, I utilize a suitable form of cutting or punching mechanism provided with suitable corner cutters H and movable toward and coöperable with female cutters H' and having also male and female intermediate notch cutters I and I'. The several male cutters are adjustably attached by bolts or other fastening means 10 to a head 11 or carrier which may be operated in any suitable manner toward and from a bed or support 12 upon which the complementary female members are provided, these latter also being relatively adjustable to the bed 12 and adapted to be secured thereon by bolts or other fastening means 10. One or the other of the members 11 and 12, the latter in the present instance, is provided with a set of edge gages 15 adjustably secured to the respective member as by bolts or screws 16.

With this apparatus, the process of manufacturing a blank of the given size is to set the edge gages 15 with respect to the several

- cutters, a distance sufficient to produce notches as $h-h$ and $i-i$ of the requisite depth into the edge of the blank and to set the respective cutters $H-H'$ and the cutters $I-I'$ in suitable disposition to each other by loosening up their fastening screws or bolts 10, these cutters being provided with holders having means permitting relative adjustment to each other and shown in the present instance, as being provided with slots 10' through which the bolts pass. Having adjusted the cutters with relation to each other so as to produce the notches $i-i$ at the pre-determined distances, the blank is then inserted until it has proper engagement with the edge gages 15 and then the apparatus operated so that the cutters sever the chips from the blank at the places pre-determined.
- 20 While it is preferably that the apparatus may be utilized for cutting all of the notches

in both edges of the blank at one time, the cutting of one edge only may be practised, if it is desired, the form of the apparatus illustrated in Fig. 3 being but one-half of 25 a duplicate set of cutters arranged at the opposite side of the apparatus, so that all of the cuts may be made at one time.

What is claimed is:

An apparatus for notching the cut bodies of suit cases, comprising in combination, a table, a head, adjustable end and side stops mounted on one of said members and a plurality of complementary cutters, said cutters comprising vertical and angularly disposed cutting edges, bases perpendicular thereto and each provided with a slot whereby said cutters may be independently adjusted, alined and removably secured to said table and head. 40

In testimony whereof I affix my signature,
HENRY L. PLUMMER,
